UNITED STATES PATENT OFFICE.

WILLIE BURCH, OF LOWELL, MICHIGAN.

RAIL-SUPPORT AND RAIL.

1,026,341.

Specification of Letters Patent. Patented May 14, 1912.

Application filed September 22, 1910. Serial No. 583,285.

To all whom it may concern:

Be it known that I, WILLIE BURCH, citizen of the United States, residing at Lowell, in the county of Kent and State of Michigan, have invented certain new and useful Improvements in Rail-Supports and Rails, of which the following is a specification.

My invention relates to the construction of the roadbed of railways and particularly to an improved rail support therefor designed to take the place of the ordinary tie, and to an improved rail particularly designed with reference to the support and to means whereby the rail and support are connected together.

The object of my invention is to provide a support for railway rails which will afford a thoroughly firm and rigid foundation for the support of the rail, this support being made of thin metal and being of such form as to secure a maximum of strength at a minimum of expense.

A further object is to provide a rail support of the character described, within which earth or other ballast may be tamped after the support is in place with the rail thereon.

A further object of the invention is to provide a support of the character described, so connected to the rail that, while the rail is held in thoroughly rigid engagement with the support, the rail may be easily removed in case it is desired to repair or replace the rail.

Another object of the invention is to provide a rail to be used in connection with the support above referred to, said rail being made in sections so that the tread section of the rail may be removed when necessary in order to replace it and the base section of the rail will remain in engagement with the rail support or base.

My invention is shown in the accompanying drawings, wherein:

Figure 1 is a plan view of a section of railway track showing my improved supports in place beneath the parallel rails. Fig. 2 is a section on the line 2—2 of Fig. 1. Fig. 3 is a perspective view of one of the dish-shaped supporting members removed. Fig. 4 is a perspective view of a portion of the transverse cross bar. Fig. 5 is a perspective view of the two cover plates used to cover the tamping openings. Fig. 6 is a transverse view of the rail disassembled, and

Fig. 7 is an enlarged sectional view on the line 7—7 of Fig. 1.

Corresponding and like parts are referred to in the following description and indicated in all the views of the accompanying drawings by the same reference characters.

Referring now to Figs. 2 and 6, 2 designates the tread section of my improved rail, and 3 the base section thereof. The tread section 2 has no base flange such as usually found in railway rails and the base section is provided with upwardly extending spaced parallel flanges 4 which define a socket 5 within which the web of the rail 2 fits and is supported. The flanges 4 extend up sufficiently upon the web of the rail 2 so that the tread section of the rail is thoroughly well supported. The tread section of the rail is held in place upon the base section by means of the set screws 6 or in any suitable manner. 5 designates a wooden filling.

For supporting the rails of the construction above described I provide, as shown in Fig. 1, pairs of concavo-convex supporting members which are placed at intervals along the length of each rail, these supporting members being connected to each other by transverse tie rods or bars, as will be more fully described. In detail each of said supporting members consists of a concavo-convex casing 7 which is downwardly dished, the upper face of the supporting member being relatively flat at its middle portion so as to permit the rail to rest thereon. The sides of the casing 7 extend outwardly and downwardly as above described and are then outwardly flanged as at 8, these flanges being notched as at 9, the notches being placed at a distance of 90 degrees from each other. The central portion of the casing has four segmental openings 10 which are spaced from each other so as to leave the cross webs 11, 11^a. These openings 10 are for the purpose of tamping earth, cinders, broken stone, or other ballast into the interior of the dish-shaped casing 7 so as to provide a relatively solid filling for the casing 7. This filling might be made of concrete if desired.

Connecting opposite supporting members 7 or casings is the transversely extending cross bar 12, this cross bar being T-shaped in cross section, as shown in Fig. 4. For the purpose of accommodating the downwardly extending middle web 13 of the cross bar

and the cross bar itself, the web 11^a is depressed along its middle as at 14^a, this depressed portion being slotted as at 14. The body of the cross bar fits within this depressed portion 14^a, and the web 13 fits within the slot so that the face of the cross bar is level with the face of the support 7. The cross bar projects at each end beyond the outer portion of the rail support, as shown in Fig. 2. The cross bar 12 is connected to the flange 8 at opposite points by means of the upwardly and outwardly inclined bolts 15. These bolts pass through the cross bar and the heads of the bolts are received beneath the flange 8, the shanks of the bolts passing through the notches 9. The bolts are surrounded by the sleeves 16 which act as spacing sleeves between the cross bar and the flange 8 and also act to separate the cross bar from the flange 8, this flange being of course solidly supported against the ground or ballast of the roadbed.

In order to hold the rail base 3 upon the supporting casing 7 the cross bar is provided with the bolt openings 17, a pair for each rail base.

The tamping holes or openings 10 should of course be covered so as to prevent any water from entering at these openings and soaking into the earth or ballast which fills the interior of the supporting casing 7. For this purpose I have provided the covering plates 18, shown in Fig. 5, which in the form of my invention illustrated are each adapted to extend across two of the openings 10 and also across the upper face of the cross bar 12. These plates are semi-circular in plan and the middle of each plate is channeled as at 19, this channel fitting over and accommodating the cross bar 12 and the plate fitting upon the upper face of the supporting casing. The channel portion 19 is formed with a bolt hole 20 at its extremity through which a cover bolt 21 passes which extends down through the cross bar 12.

The straight edge of the cover plate is cut away at its middle as at 22 so that the edge of the plate on each side of the channel portion 19 may be slipped beneath the rail base 3 and thus the rail assists in holding the covers in place. The covers, however, may be easily removed in order to permit the rail supporting casing 7 to be refilled with earth and retamped, it being only necessary to remove the bolt 21 whereupon the cover may be easily withdrawn from its engagement beneath the rail base 3. If desired bolts 24 may pass through the flange of the rail and extend into the notches 9 immediately beneath.

It will be seen that I have provided a rail support which has many advantages over the ordinary tie, or over a support which extends transversely beneath both of the

rails of the track. It will be seen that I have provided a support which is very light and which, because of its peculiar shape, is very strong and that this support is so constructed that it may be filled interiorly with earth, concrete, or rock ballast and so held firmly in place, while at the same time protecting the interior filling from moisture and from being washed away. Furthermore the inclined sides of the support afford a means whereby the ballast of the road may be filled in over and around the supporting base 7, thus holding the base in rigid relation to the track and preventing any shifting thereof. As each rail is provided with its own supporting members or bases, it is obvious that the rail may be shifted or its elevation changed without having to disturb the position of the parallel rail. This permits the track to be more easily repaired and kept in good order than is possible where a tie or other supporting member extends entirely beneath both rails.

The peculiar form of my rails permits the treads thereof to be easily removed when the rails are worn and new treads substituted without the necessity of removing the spike or other means for holding the rails in place and without requiring any realignment of the rail, as is necessary with the present construction.

My invention is simple, may be easily and cheaply constructed and is thoroughly effective as a rail support.

Having thus described my invention, what is claimed as new is:

1. A support for railway rails, comprising a hollow annular casing having a relatively flat circular top for the support of the rail and an outwardly and downwardly flared wall, said wall being flanged at its lower margin, and fastening devices passing through said rail and through the said flange.

2. A support for railway rails, comprising a hollow circular casing having an outwardly and downwardly flared annular wall, the top of said casing being relatively flat and formed with filling openings, through which a filling material may be tamped into the interior of the casing, and covers for said filling openings.

3. A support for railway rails, comprising a hollow circular casing having an outwardly and downwardly flared annular wall, the top of said casing being flat for the support of a rail and provided with a series of segmental filling openings, and covering plates for said openings detachably engaged with the top of the casing.

4. The combination with parallel railway rails, of supports therefor, each comprising a hollow annular casing disposed beneath each rail and having a relatively flat top, an outwardly and downwardly flared

annular wall, a cross bar extending transversely beneath both of said rails and resting upon the said casings to which the rails are bolted, and means connecting the cross bar with the annular casings.

5. The combination with the parallel rails of a railway track, of a plurality of pairs of supports located beneath the rails, each support comprising a hollow annular casing having a relatively flat top, an outwardly and downwardly annularly flared wall, the lower margin of the annular wall being outwardly flanged, a cross bar extending transversely beneath the rails and bolted to the said rails, and fastening devices extending downward from the cross bar and connecting the cross bar to the flanged margins of the supports.

6. The combination with the parallel rails of a railway track, of a plurality of pairs of supports therefor located beneath said rails and supporting the same, said supports each comprising a hollow annular casing having a relatively flat top and an outwardly and downwardly flared annular wall, the flat top of the casing being transversely slotted, a cross bar extending transversely beneath the rail and connecting each pair of supports, said cross bar being T-shaped in cross section, the downwardly extending web of the cross bar being disposed within the slots of the supporting casings, bolts connecting the rails to said cross bar and fastening devices connecting the cross bar to the said supporting casings.

7. The combination with the parallel rails of a railway track, of a plurality of pairs of supports therefor, each support comprising a hollow annular casing disposed beneath one of the rails, each casing having a relatively flat top and a downwardly and outwardly flared annular wall, the top of the casing being transversely slotted and provided with segmental tamping openings located on each side of the slot, a connecting cross bar T-shaped in cross section extending beneath each pair of supporting casings, the depending web of the cross bar being disposed within said transversely extending slots of the casings, the rails being bolted to said cross bar, fastening devices connecting the cross bar to the said supporting casings, and covering plates extending over said cross bar and covering the tamping openings, said covering plates having flanges extending beneath the adjacent rail and being bolted to the top of the said supporting casing.

8. The combination with parallel railway rails, of supports therefor, each comprising a hollow casing disposed beneath a rail and open at the bottom, the side of said casing being outwardly and downwardly flared, a cross bar extending transversely beneath both of said rails and resting upon the casings, to which cross bar the rails are attached, and means disposed upon the top of said casings extending over the cross bar and holding it to each casing.

9. The combination with parallel railway rails, of supports therefor, each comprising a hollow, open bottom casing disposed beneath a rail, each casing having an outwardly and downwardly flared outer wall, the top of each casing being slotted, and a cross bar extending transversely beneath both of said rails and resting upon said casings, said cross bar being T-shaped in cross section and the web thereof extending into said slots in the tops of the casings.

10. The combination with parallel railway rails, of supports therefor, each comprising a hollow annular casing disposed beneath a rail and having a relatively flat top and an outwardly and downwardly flared annular wall, the flat top of each casing being slotted and depressed on each side of the slot, a T-shaped cross bar extending beneath both of said rails and resting in the depressed portion of each casing, the web of the cross bar extending into the slot in each casing, and fastening devices connecting the cross bar with the casings.

11. The combination with parallel railway rails, of supports therefor, each comprising a hollow casing, disposed beneath the rail and open at the bottom, the sides of said casing being outwardly and downwardly flared, a tie-bar extending transversely beneath both of said rails and resting upon the casings, means for attaching the rails to the tie-bar, and means for holding the tie-bar in place upon the casings.

12. The combination with parallel railway rails, of supports therefor, each support consisting of a hollow casing disposed beneath a rail and open at the bottom, the sides of said casing being outwardly and downwardly flared, a tie-bar extending transversely beneath both of said rails, and resting upon the casing, to which tie-bar the rails are attached, and means for clamping the tie-bar to the casings.

13. The combination with parallel railway rails, of supports therefor, each comprising a hollow open bottomed casing disposed beneath a rail, each casing having outwardly and downwardly flared outer walls, the top of said casing being open and formed with a diametrically extending web extending parallel to the rail supported on the casing, and a tie-bar extending transversely beneath both of said rails and across the open upper ends of the casings at right angles to the web, and means for clamping said tie-bar to the casings and the rails to said tie-bar.

14. The combination with parallel railway rails, of supports therefor, each comprising a hollow open bottomed casing dis-

posed beneath a rail, each casing having downwardly and outwardly flared walls, the top of each casing being slotted, and a tie-bar **T**-shaped in cross section extending transversely beneath both of said rails and resting upon said casings, the web thereof extending into slots in the tops of the casings, means for clamping the rails upon the tie-bar, and means for detachably holding the tie-bar to the casings.

15. A support for railway rails comprising a hollow casing having a downwardly ex-

tending side wall, said casing being open at its top, a transversely extending rail supporting tie-bar resting on the upper end of the casing, means for detachably connecting the tie-bar with the casing, and means for clamping a rail to said tie-bar.

In testimony whereof, I affix my signature in presence of two witnesses.
